UNITED STATES PATENT OFFICE.

JAMES STONE, OF LA CROSSE, WISCONSIN.

LAP-BOARD.

1,286,442.

Specification of Letters Patent.

Patented Dec. 3, 1918.

Application filed September 23, 1916. Serial No. 122,781.

To all whom it may concern:

Be it known that I, JAMES STONE, a citizen of the United States, residing at La Crosse, in the county of La Crosse and State 5 of Wisconsin, have invented new and useful Improvements in Lap-Boards, of which the following is a specification.

This invention relates to a lap-board of that type which may be folded or rolled up 10 into a compact article when not in use, and unfolded and held distended and flat when in use.

My prior Patent No. 1,106,901, granted August 11, 1914, shows a lap-board of the 15 class referred to, and it is among the objects of my present invention to improve in particular the type of means employed for holding the board distended and flat when in use.

The invention consists further in the matter 20 hereinafter described and more particularly pointed out in the appended claims.

In the accompanying drawings:

Figure 1 is a bottom plan view of a lap-board embodying the features of my invention 25 and showing the distending or extension bars collapsed or nested, preparatory to either being swung into positions for holding the board flat and distended or rolling the same up into a compact article for transportation or storage;

Fig. 2 is a similar plan view of said board and showing the extension bars swung into positions prior to being engaged one with the other;

Fig. 3 is a like plan view of the board and showing the extension bars in the positions they occupy when holding the board distended and flat for use;

Fig. 4 is a detail sectional view taken on 40 line 4—4 of Fig. 3;

Fig. 5 is a detail sectional view taken on line 5—5 of Fig. 3;

Fig. 6 is a detail sectional view taken on line 6—6 of Fig. 1;

Fig. 7 is a view of the board when rolled up into a compact article for either transportation or storage;

Fig. 8 is a perspective view of the free end of one of the distending bars and showing 50 the locking tongue provided at the end of said bar;

Fig. 9 is a perspective view of the free end of one of the other distending bars and showing the locking notch provided adjacent 55 the end of such bar; and

Fig. 10 is a perspective view of one end of

the intermediate metal strip and showing the locking shoulder provided adjacent the end thereof.

As shown in the accompanying drawings, 60 a lap-board embodying the features of my invention comprises a foldable body portion 10, substantially rectangular in shape and which may be made either of a single layer of flexible material, such as cloth, leather, 65 or the like, or, as shown in the drawings, of two superposed layers of such material, the upper layer 11, which serves as the top surface of the board when in use, being joined to the lower layer 12 at spaced intervals by 70 transversely extending, parallel lines of stitching to form a plurality of transversely extending, parallel pockets, in which are inserted relatively flat, stiffening strips 13, the latter being preferably made of a light 75 material, such as fiber-board or vulcanized fiber, in order to aid in reducing the weight of the completed board to a minimum. The 80 pockets are preferably so formed as to extend across the board parallel to each other and to the end edges of said board, thereby permitting the board to be folded or rolled up endwise and thus produce a folded article of a length no greater than the width of the board. Moreover, the formation of 85 the pockets is such that the upper layer 11 will be held flat and smooth when the board is distended and in use, this construction affording a smooth top surface, which makes 90 the board more available for use in the sewing room, for card players, and the like.

For holding the body portion 10 taut, flat, and smooth, when the board is distended and in use, I provide the following construction. Extending across the board at each end 95 thereof is a stiffening member 14, 14, which is preferably made in the form of a strip of sheet metal bent so as to have the cross-sectional shape, as best shown in Figs. 5 and 6. Thus, each stiffening member may be readily 100 secured to the body portion 10 by clamping the end marginal part thereof in the channel 15 formed between the double flange 16 of said metal member 14. (See Figs. 5 and 6.) Said member 14 is also provided with 105 an outwardly projecting longitudinal flange 17, which serves as a stiffening rib for such member. Located beneath the board and at each end thereof is a pair of distending or extension bars 18, 19, the latter being prefer- 110 ably made of sheet metal and channel-shaped in cross-section, as best shown in Figs. 4, 5,

6, 8, and 9, so that the bars of each pair may be nested and span the folded edge of the flange 16 of the associated member 14, when said bars are collapsed or swung into the position shown in Fig. 1, preparatory to rolling up the board. As shown, the bar 19 of each pair is the outermost one, when the bars are nested. Each bar 18, 19 of each pair is pivotally connected at one end by a pivot pin 20 to one end of the associated member 14. As illustrated, each bar 18, 19 is no longer than the width of the board, and when distended said bars are swung about their pivot pins into positions extending lengthwise of the board, with the free end portion of one bar overlapping and interfitting within the free end portion of the corresponding bar of the opposite pair, as clearly shown in Figs. 3 and 4. As clearly shown in Fig. 5, the pivoted end of the bar is bifurcated to provide spaced flanges 21, 21, which span the folded edge of the flange 16, the pivot pin 20 being inserted through such parts and the portion of the body 10 in the channel 15. (See Fig. 5.) Each bar is provided adjacent its pivoted end with a stop shoulder 22 adapted to contact with the folded edge of the flange 16 and thereby prevent the bar from being swung outward beyond its fully extended position, as shown in Fig. 3.

In order to lock the free ends of the bars 18, 19 of one pair with the similar ends of the corresponding bars of the opposite pair, when said bars are extended for holding the body portion 10 of the board taut, flat, and smooth and, further, prevent such locked ends from being accidentally disconnected while the board is in use, I provide each bar of each pair with a locking member adapted to engage the locking member of the corresponding bar of the opposite pair when said bars are swung into their extended positions. As shown in the drawings, one of the bars of each pair, preferably the bar 18, is provided adjacent its free end with an inclined locking notch 26 opening outwardly through the back or folded edge of said bar, while the other bar 19 of the same pair is provided at its free end with a locking tongue 27, adapted to extend into said locking notch when the bars are locked together. The bars 18, 19 of each pair are of such length that the free ends of the corresponding bars of the opposite pairs meet before the bars reach their fully extended positions, as shown in Fig. 2. Moreover, the locking notch 26 in each bar 18 is so arranged in relation to the length of the bar that the locking tongue 27 of the bar 19 of the opposite pair engages in said notch before the bars reach their fully extended positions. After the ends of the bars become interlocked, it is necessary to forcibly move the bars into their fully extended positions before such bars will act to hold the body portion 10 of the board taut

and flat. Thus, the bars have the effect of being materially elongated and serve to place the body portion 10 under tension lengthwise and effect the holding of said body portion taut, flat, and smooth, when the board is distended for use.

The stop shoulders 22, 22 prevent the bars, after being interlocked at their overlapping ends, from being swung beyond their fully extended positions, but, in order to prevent the interlocked ends of the bars from being accidentally disconnected, as would happen should the bars be swung inwardly, I provide, midway between the ends of the board, a metal strip 28, the latter extending fully across the board on the under side thereof and being secured thereto at intervals in its length, and having its ends concealed by a marginal flap 29 sewed over the side edges of said body portion 10. Said flap 29 also serves to close the open ends of the pockets in which the stiffening members 13 are inserted and, additionally, to provide a suitable finish or trimming for the sides of the board. Said metal strip 28 is provided with an outwardly projecting rib or flange 30, the ends of which terminate short of the ends of the strip 28. Said flange 30 not only serves as a stiffening rib, but also as part of the locking means to be now described. Each end of said flange 30 is undercut to provide a locking shoulder 31, as shown in Fig. 4, said shoulder serving to engage the inner edge of one of the bars, when interlocked, so as to prevent said bars from being accidentally moved inward and thus becoming disconnected.

To set up the board, the latter is unfolded and laid out flatwise, as shown in Fig. 1, with its under side facing upwardly. At such time the extension bars 18, 19 occupy the positions shown in said figure. The bars are then swung outwardly into the positions shown in Fig. 2, whereupon the bars are moved until the locking tongue 27 on one engages the locking notch 26 on the other. At such time the bars are connected together and are forced outwardly toward the associated side margin of the board. The bars are made long enough so that when forced outwardly, after being connected together, they will place the body 10 under tension and hold the same taut and flat when moved into their fully extended positions, as shown in Fig. 3. The bars, being made channel-shape in cross-section, interfit one within the other, as shown in said Fig. 3. When the bars have been interlocked and moved into their fully extended positions, the same engage the locking members 31, 31 on the flange 30 and thus are held from being accidentally moved inward and disconnected one from the other. To collapse the board, the interlocked bars are raised or moved from engagement with the shoulders 31, 31

and swung into their positions overlapping one another and the folded edges of the flanges 16 of the end members 14, 14, whereupon the board may be rolled up endwise in order to produce a compact article.

In order to hold the folded package in its rolled form, I provide a strap or tape 32 secured at one end to the under side of the board, adjacent one of the end members 14, 10 as shown in Fig. 1. Said strap is provided at its free end with one member 33 of a snap fastener, and intermediate its ends with the other member 34 of such fastener. Manifestly, the board is rolled up with the opposite end member 14 within the center of the package, so that the strap or tape 32 may encircle the outside of the rolled package and its snap fasteners engage one with the other, as shown in Fig. 7. 15

20 The intermediate strip 28 may be secured to the body of the board in any suitable manner, but, as shown in Fig. 10, the flange 30 is provided with a plurality of longitudinally spaced, transverse holes or apertures 35 33, through which threads may be passed for sewing said strip to said board.

Although I have shown and described herein in detail one form in which a device embodying the features of my invention may be made, yet it is to be of course understood that I may variously modify and change the details of construction and arrangement of the parts shown, without departing from the spirit or scope of my invention, and I do not 30 want to be limited to the exact details of construction and arrangement of parts shown, except as pointed out in the appended claims.

I claim as my invention:

40 1. A device of the character described, comprising a foldable body portion, and two pairs of distending bars, one pair at each end of said body portion, the bars of each pair each having pivotal connection at one end with one end of said body portion, said bars when distended being swung into positions extending lengthwise of said body portion and each bar being provided with locking means adapted to engage and interlock with the locking means on one of the bars of the opposite pair before said bars reach their fully extended positions.

2. A device of the character described, comprising a foldable body portion, a stiffening member secured to said body portion at each end thereof, two pairs of distending bars, one pair at each end of said body portion, the bars of each pair each having pivotal connection at one end with one end of the associated stiffening member, said bars when distended being swung into positions extending lengthwise of said body portion and having their meeting ends interlocked with each other, and means on said body portion adapted to engage said bars for holding

the interlocked ends thereof from being accidentally disconnected.

3. A device of the character described, comprising a foldable body portion, a stiffening member secured to said body portion at each end thereof, and two pairs of distending bars, one pair at each end of said body portion, the bars of each pair each having pivotal connection at one end with one end of the associated stiffening member, said bars when distended being swung into positions extending lengthwise of said body portion, and each bar being provided at its free end with a locking member adapted to engage and interlock with the locking member on one of the bars of the opposite pair before said bars reach their fully extended positions.

4. A device of the character described, comprising a foldable body portion, a stiffening member secured to said body portion at each end thereof, two pairs of distending bars, one pair at each end of said body portion, the bars of each pair each having pivotal connection at one end with one end of the associated stiffening member, said bars when distended being swung into positions extending lengthwise of said body portion, each bar being provided at its free end with a locking member adapted to engage and interlock with the locking member on one of the bars of the opposite pair, before said bars reach their fully extended positions, and fastening members on said body portion adapted to engage said bars for holding the interlocked ends thereof from being accidentally disconnected.

5. A device of the character described, comprising a foldable body portion, and two pairs of distending bars, one pair at each end of said body portion, the bars of each pair each having pivotal connection at one end with one end of the body portion, said bars when distended being swung into positions extending lengthwise of said body portion, one bar of each pair being provided with a locking notch and the other bar of each pair being provided with a locking tongue adapted to engage the locking notch in one of the bars of the opposite pair before said bars reach their fully extended positions.

6. A device of the character described, comprising a foldable body portion, a stiffening strip secured to said body portion at each end thereof, two pairs of distending bars, one pair at each end of said body portion, the bars of each pair each having pivotal connection at one end with one end of the associated stiffening strip, said bars when distended being swung into positions extending lengthwise of said body portion, one bar of each pair being provided with a locking notch and the other bar being provided with a locking tongue adapted to engage the locking notch on one of the bars of the opposite pair before said bars reach their fully ex-

tended positions, and means on the body portion adapted to engage said bars for holding the interlocked ends thereof from being accidentally disconnected.

- 5 7. A device of the character described, comprising a foldable body portion, a metal strip secured to said body portion at each end thereof, two pairs of distending bars, one pair at each end of said body portion, the 10 bars of each pair having pivotal connection at one end with one end of the associated metal strip; the bars of each pair being channel-shaped and adapted to nest one within the other when swung into positions 15 extending alongside of their associated metal strip, said bars when distended being swung into positions extending lengthwise of said body portion with their free ends overlapping and fitting one within the other, one 20 bar of each pair being provided with a locking notch and the other bar being provided with a locking tongue adapted to engage the locking notch in one of the bars of the opposite pair when said bars are distended, and 25 fastening members on said body portion adapted to engage the overlapped ends of said bars for preventing the same from being accidentally disconnected.

8. A device of the character described, 30 comprising a foldable body portion, a metal strip secured to said body portion at each

end thereof, two pairs of distending bars, one pair at each end of said body portion, the bars of each pair each having pivotal connection at one end with one end of the associated metal strip; the bars of each pair being channel-shaped and adapted to nest one within the other when said bars are swung toward each other into positions extending along the associated metal strip; the bars 35 when distended being swung outward from each other into positions extending lengthwise of said body portion with their free ends overlapping and interfitting one within the other, one bar of each pair being provided with a locking notch and the other bar being provided with a locking tongue adapted to engage the locking notch in one of the bars of the opposite pair, when said bars are distended, and a third metal strip secured to 40 said body portion intermediate the ends thereof and provided adjacent each end with a locking shoulder adapted to be engaged by said bars when extended.

In testimony that I claim the foregoing as my invention, I affix my signature in the presence of two witnesses, this 26th day of September, A. D. 1916.

JAMES STONE.
